UNITED STATES PATENT OFFICE

JACQUE C. MORRELL, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

VAPOR FRACTIONATION

Application filed April 25, 1927. Serial No. 186,218.

The present improvements relate more particularly to a process and apparatus designed for the efficient fractionation of vapors whereby the sufficiently converted fractions will be separated from the insufficiently converted fractions, and the latter returned for retreatment.

The present invention is particularly applicable to the fractionation of heated hydrocarbon vapors produced in the cracking or distillation of the hydrocarbon oil, but it is to be understood that in its broad concept, the invention is adapted for the fractionation of vapors from any source.

15 The invention is adapted to be carried out under atmospheric, superatmospheric, or subatmospheric pressure.

In the fractionation of hydrocarbon oil vapors, particularly those produced in the cracking and conversion of hydrocarbon oil under conditions of heat and superatmospheric pressure, it is desirable that maximum intimate contact be had between the vapors and the cooling liquid. It has 25 also been found to be of advantage to maintain pools of liquid in separate stages in the fractionating instrumentality whereby there is a tendency toward equilibrium between the liquid and vapors in each stage, and of more 30 importance, advantage is taken of the time element during which the liquid in the different pools is subjected to the varying conditions within the instrumentality. The vapors which escape condensation, and which 35 are removed from the upper end of the fractionating instrumentality will be found to be substantially uniform in composition, and upon testing will be found to have been efficiently fractionated.

40 In such types of fractionating towers wherein a body of liquid is maintained upon a deck, and the vapors ascend through openings in a cap over a vapor riser above the body of liquid where the velocity of the 45 vapors is high, entrainment may occur so that the liquid descending through the risers in the deck will be held back, thus interfering with the proper operation of the tower. This may be avoided by designing the tower 50 so as to have a low vapor velocity through

the risers and also relieving the deck of some of its liquid by orifices in the deck plate.

Another method of avoiding entrainment, which comprises the subject matter of the present invention, insures the positive descent of desired quantities of the liquid by having a down-flow pipe or a series of down-flow pipes in the deck through which substantially all of the liquid is caused to descend, permitting at the same time free ascent 60 of the vapors through the risers, which ascent may be at a low, or even a high velocity. Entrainment of the descending liquid through the down-flow pipes, is avoided by maintaining a liquid seal. 65

The utility of the invention, as well as various objects and advantages will be more apparent from the following description.

In the drawings, Fig. 1 is a vertical sectional view of a fractionating tower equipped 70 to carry out the purpose of the present invention.

Fig. 2 is a cross sectional view taken on line 2—2 of Fig. 1.

Fig. 3 is a cross sectional view taken on 75 line 3—3 of Fig. 1.

Fig. 4 is an enlarged fragmentary vertical sectional view of the deck illustrating the cap, vapor risers, down-flow pipes and liquid seal. 80

Referring more particularly to the drawings, 1 designates a shell which may be disposed vertically and which may take any form. This shell may take the form of the usual metal fractionating tower provided with 85 the covers 2 through which the shell may be cleaned. The shell may also be provided with vapor inlet 3 in which may be interposed the valve 4, the vapor outlet 5 in which may be interposed the valve 6, the liquid inlet 7 in 90 which may be interposed the valve 8, and liquid outlet 9 controlled by the valve 10. Disposed within the shell and spaced suitable distances from each other, are a number of decks 11 which may be supported on the annular lugs 12, if desired. Each of the decks 11 is provided with a number of vapor risers 13 projecting above the surface of the deck, over the upper end of which are placed the caps 14. As a feature of the invention, each 100

of the caps may comprise an annular flange 15, the lower edge of which is disposed a short distance above the surface of the deck 11 and the upper edge connected to a roof 16, which roof may slope toward its edge from the central point indicated. Perforations 17 may be provided in that portion of the annular flange 15 which lies between the upper edge of the vapor riser 13 and the point of connection to the roof 16, the purpose of which will be hereinafter more particularly explained. Downflow pipes 18 are positioned in each deck 11, having a portion projecting above and below the deck. The height of the down-flow pipe within the deck 11 is carefully computed, and is preferably such as to maintain a pool of liquid on each deck 11, the arrangement being such that the liquid will over-flow the upper edge of the down pipe and flow therethrough, collecting in an imperforate depression 19 formed in the perforated plate 20.

The descending liquid spreads out over the perforated plate, and is distributed on the caps in the deck below, it being understood that the relative size and number of the perforations is so computed that no substantial amount of liquid will collect thereupon. The arrangement is such that a perforated plate or grid 20 is positioned between each of the first mentioned plates or decks 11, which carry the risers 13 and downflow pipe 18, but which are otherwise imperforate.

The operation is as follows: Heated vapors enter through the vapor line 3 into the interior of the shell 1 and pass upwardly through the perforations in the perforated plate 20, after which they ascend through the vapor risers 13 and through the orifices 17 in the annular flange 15 of the cap. Liquid will collect on the deck 11, building up to a height depending upon the height of the down-flow pipe 18. Excess liquid will overflow the upper edge of the down-flow pipe 18 and will collect in the depressed portion 19, which in effect forms a liquid seal to prevent the vapors from ascending through the down pipe 18 and thus preventing the entrainment of liquid which is descending in the down pipe 18.

It is to be noted that the lower edge of this down pipe 18 is below the upper surface of the plate 20 whereby a small pool of liquid will collect.

From the foregoing, it will be apparent that efficient fractionation will take place as the vapors ascend through the tower. In each step of the fractionating tower, an equilibrium will be maintained between the liquid and vapors so that there is a progressive temperature change throughout the tower. The vapors which escape condensation and which are removed through the vapor outlet 5, will be found to be of substantially uniform composition. It is to be noted that intimate con-

tact, equilibrium between vapors and liquid in each step, and time element for the pools of liquid, all of which are desirable features, are brought about by the present invention without having the vapors bubble up through pools of liquid.

It is to be noted that there may be any number of decks or plates 11 and 20 properly spaced throughout the height of the tower. The number of vapor risers 13 and caps 16 in each deck 11 will vary with the size and capacity of the tower and also will depend on whether a high or low vapor velocity is desired therein. The number and size of over-flow pipes 18 may of course, vary.

It is to be noted that the vapors are permitted to have a free upward passage through the risers while the over-flow liquid is caused to have a free downward passage through the over-flow down pipes 18. This free passage of vapors and liquid is brought about without sacrifice of the desired intimate contact between the vapors and liquid which is brought about when the vapors pass through the orifices 17 and through films of liquid which are flowing downward along the wall of the flange 15. The vapors will also have contact with the liquid flowing in film form downwardly on the roof 16, and in addition to this, contact will be effected in the space between the upper surface of the deck 11 and the lower surface of the deck 20. The perforated plate 20 may, if desired, take the form of a screen provided with the imperforate portions 19. The amount and character of cooling liquid introduced through the line 7, will of course, depend upon the conditions of operation, as is well known to those versed in this art. The liquid which remains uncondensed, and which collects in the bottom of the shell 1, may be withdrawn through the line 9, and may be returned for retreatment, if desired, in either the same or a separate process.

I claim as my invention:

A dephlegmator comprising in combination a shell having vapor and liquid inlets and outlets, spaced superimposed imperforate decks mounted within said shell, perforate decks mounted therebetween, relatively short upstanding open end risers projecting above the general plane of each of said first mentioned decks, a cap mounted above each riser, each cap comprising a flange having perforations above the upper end of the associated riser and a top wall, and a liquid overflow pipe projecting above and below each of said first mentioned decks, and imperforate depressions in each perforate deck in which the overflowing liquid collects, said imperforate depressions forming a liquid seal.

In testimony whereof I affix my signature.
JACQUE C. MORRELL.
